JOHN E. WOOD, OF DALTON, MASSACHUSETTS, ASSIGNOR TO PITTSFIELD SPARK COIL COMPANY, OF DALTON, MASSACHUSETTS, A CORPORATION OF MASSACHUSETTS.

ELECTRIC SWITCH.

1,048,119.

Specification of Letters Patent. Patented Dec. 24, 1912.

Application filed January 3, 1912. Serial No. 669,163.

To all whom it may concern:

Be it known that I, JOHN E. WOOD, a citizen of the United States of America, residing at Dalton, in the county of Berkshire and State of Massachusetts, have invented new and useful Improvements in Electric Switches, of which the following is a specification.

This invention relates to improvements in 10 electric switches for connecting and disconnecting different sources of electric energy as used in connection with the ignition devices for internal combustion engines, as for example, two different sets of batteries, 15 either primary or storage; or a battery and magneto may be connected.

The particular object of this invention is to provide means to securely lock the switch-lever against operation when not in use; and, 20 second, to permit the switch-lever to readily operate from one position to another.

In general, the invention consists of a base-piece of suitable insulating material having contact members mounted thereon, a 25 switch-lever adapted to form a contact with said members, and means for locking the lever against operation when not in use but permitting the lever to be readily unlocked when the switch is to be used to make the 30 proper electrical connections to the ignition devices.

In the drawings forming part of this application,—Figure 1 is a plan view with the cover removed and illustrating the switch-lever in a locked position. Fig. 2 is a view similar to Fig. 1 but showing the lever unlocked or so that it may readily be moved over the contact members. Fig. 3 is a vertical, sectional view on the line 3—3 of Fig. 40 1, with the key removed. Fig. 4 is a view similar to Fig. 3 with the key inserted and the slotted barrel member moved or turned so that the switch lever can be operated in either direction.

45 Referring to the drawings in detail, *a* designates the base member of the switch; *b* the cap member secured thereto by any suitable means, as screws, which enter threaded sockets *c* in the base member.

50 *d*, *e*, and *f* designate contact members to which the terminals from the sources of electrical energy are connected.

55 *h* is a switch-lever pivoted to the base member *a* by means of the pivot construction *i*. The inner end of the switch-lever

makes contact with the contact members *d*, *e*, and *f*. Suitable devices for retaining the switch-lever *h* in its contact positions with relation to the contact member consists of a plate *j* having depressions *k* therein to receive a ball *m* which is normally held or pressed downwardly by means of an elastic plate *o*, the inner end of which moves over the contact members. The switch-lever *h* is provided with an operating handle or 65 knob *p*.

The locking device proper comprises a struck-up portion or projection *q*. Located above this projection is a rotative barrel member *r* having a groove *s* cut in its lower 70 portion, which groove is for the purpose of receiving the projection *q* and is of such shape that the barrel member *r* may be turned about the projection by means of the key *t*, either to lock the switch-lever *h* 75 against movement, as shown in Fig. 1, or permit the projection *q* to pass freely through this groove, as shown in Figs. 2 and 4. The key *t* and the thimble *u* are so constructed that the key can be removed 80 only when the switch-lever *h* is in a locked position, as shown in Figs. 1 and 3. A plate *w* is mounted for rotation in the thimble *u* and is provided with a slit therein to permit the key to be inserted as in the well known 85 "Yale" lock construction. The wings *x* on the key *t* prevent its removal when the thimble *u* is in the position shown in Figs. 1 and 4, as they are then under the projections *y*. 90

It will be noticed that the projection *q* and the center portion of the groove *s* is of such shape that the barrel member *r* can be turned from the position shown in Fig. 1 to that shown in Fig. 2; that is to say, the center portion of the groove *s* is slightly concave, as shown at 3. When the groove *s* in the barrel member *r* is in the position shown in Figs. 2 and 4, the projection *q* 100 simply passes through the groove permitting the lever to be swung from right to left and vice versa. Figs. 1 and 3 show the barrel *r* turned so that the groove *s* stands transverse to the projection *q*. The lever is then locked and the key may be removed 105 and the switch left, without any danger of its being moved.

The pivot pin *i*, it will be noticed, has an extension piece *i*¹ attached thereto, and threaded on this piece are nuts *i*², to hold 110

the switch lever in place, which are turned down onto the elastic plate o , as shown. A projection h^1 on the end of the lever h enters a slit o^1 of the elastic member o .

5 The switch is shown with the letters "B", "M" and the word "Off" to designate the three positions of the switch lever h , as being connected with the battery, magneto, or "off" positions of the lever.

10 What I claim, is:—

1. In a switch, the combination with a lever, of a grooved barrel device, said lever having a projection thereon which enters the grooved part of the barrel; and means 15 to operate the barrel device to change its position with relation to the projection.

2. A switch comprising a base and cap member, contact members, a contact-lever, means to retain the lever in an inoperative 20 position, said means including a member movable with the lever that is above the plane of the same, an open-ended grooved device to receive said means, and a key device to operate said device to permit the 25 lever to operate or to retain the same in an inoperative position.

3. In a switch, the combination with the contact-lever thereof, a rotative member having a recess therein, an element on the 30 lever adapted to enter the recess, a key device for operating the rotative member

whereby the lever may be retained in a locked or unlocked position.

4. In a switch, the combination of a switch lever, a base member, a cap, a rotative member in the cap, and inter-engaging devices between the lever and the rotative member to permit the lever to swing in the arc of a circle, or to be retained against movement. 40

5. In a switch, the combination with the switch-lever, of a cap member, a barrel member mounted in the cap member and having a groove in the lower portion, an element on said lever to enter the groove, a key device to operate the barrel member, means inter-engaging on said key and barrel to prevent the removal of the key device except when the lever is in a locked position. 45

6. In a switch, the combination with a switch lever, a rotatable member, an element carried by said switch lever and adapted to engage said member, a key-device to operate the member to permit the element to pass freely through the member when the switch lever is unlocked and to lock said element against movement when the member is in a different position, as described. 50

JOHN E. WOOD.
